LIFTING DEVICE

Algot Leonard Viebke, Stockholm, Sweden
Application May 2, 1955, Serial No. 505,171

1 Claim. (Cl. 254—93)

The present invention refers to such a lifting device as comprises two or more columns with sections arranged for telescopic movement in each other. Earlier such lifting devices have been provided with locking mechanisms and valves or other expensive means to make the pistons move in the correct succession and eliminate disturbing piston alterations, speed differences and varying pressure of the medium used for lifting. The present invention eliminates the need of such expensive devices. The characteristic features of the present invention are that every section in one column is combined with that or those sections in the other column or columns which is the same number of sections from a given end of the column, and that each group of combined sections has the same total pressure area. The pistons will automatically follow each other with the same speed, and as a result it is of no importance which of the piston units starts moving at the raising or lowering operation.

Further features and advantages of the invention will appear from the following description, reference being had to the accompanying diagrammatic drawing illustrating a preferred embodiment of a lifting device comprising two columns.

Fig. 1 shows a side view of said lifting device;

Fig. 2 is a sectional view along line 2—2 of Fig. 1; and

Fig. 3 is a sectional view along line 3—3 of Fig. 2.

The lifting device comprises two columns 1 and 2. Each of the columns 1 and 2 includes on one hand a cylinder 3a and 3b and on the other three sections 4a, 4b, 5a, 5b and 6a, 6b, which are telescopically movable. In column 1 the sections 4a, 5a and 6a, counting from below, have decreasing areas, whilst the sections 5b, 4b and 3b in column 2 have areas which increase from below. According to the embodiment shown the two 50 columns 1 and 2 are identical and opposed.

The sections 4a and 5b have the same common area as the sections 5a, 4b and the sections 6a, 3b, respectively. The sections 4a and 3b may thus have an area of 100 square units, the sections 5a and 4b an area of 55 86 square units and the sections 6a and 5b an area of

2

72 square units. The figures are given in a suitable unit of area. The total area of each of the above three pairs of sections is therefore 172 square units.

The two telescopic sections 4a and 5b, second from below, in the two columns 1 and 2 are united by means of angle iron 7, and the two telescopic sections 5a and 4b, which have equally large areas, are united by means of an angle iron 8. The two uppermost telescopic sections 6a and 3b are intended to be united by 10 means of a lifting platform 10 or like connecting device. The lowermost telescopic sections 3a and 6b are supported on a stationary base 11, to which they are united. By uniting the telescopic sections in the way described above a lifting device is obtained, all units of which have the same area.

In case the lifting device comprises four, six, eight etc. columns all said columns can be identical like those according to the embodiment shown, one half being directed in one direction, and the second half in the other direction. Also in this embodiment the pistons in each pair of columns can be united with each other by means of angle irons. The further connection of the pistons is then arranged in a suitable way.

The invention is not restricted to the features described above and shown in the drawing but can be varied in many ways within the scope of the appendant claim. The columns can thus be three, five, seven etc., in which case the columns need not be identical. The number of pistons in each column can of course 30 be varied within wide limits.

What I claim and desire to secure by Letters Patent is:

Hydraulic telescopic lifting apparatus comprising two parallel columns positioned beside each other, each of said columns consisting of the same number of telescopic sections and which are connected to a source of pressure medium, a base with which the lowermost telescopic section in each column is engaged, a platform connecting device with which the uppermost telescopic section in each column is engaged, the columns being arranged closely to each other, each telescopic section in one column, counting from the larger end of said column, rigidly connected to that telescopic section in the other column which is the same number of sections from the smaller end of the other column, each pair of connected sections having an equally large pressure area as the pressure area of each of the other pairs of connected sections.
